Primary Examiner — Keith J Wilson(74) *Attorney, Agent, or Firm* — Troutman Pepper Hamilton Sanders LLP; Ryan A. Schneider(57) **CLAIM**

The ornamental design for nozzles for fluid distribution, as shown and described.

DESCRIPTION

FIG. 1 is a front perspective view of our new design for a nozzle with body for fluid distribution;

FIG. 2 is a rear perspective view thereof;

FIG. 3 is a side elevation view thereof, the other side elevation view being a mirror image thereof;

FIG. 4 is a top plan view thereof, the bottom plan view being a mirror image thereof;

FIG. 5 is a front elevation view thereof; and,

FIG. 6 is a rear elevation view thereof.

The broken lines depict portions of the nozzle for fluid distribution that form no part of the claimed design.
